UNITED STATES PATENT OFFICE

1,931,566

AUTOMATIC ROTARY NUMBERING
MACHINEWilliam B. White, Nashville, Tenn., assignor to
Marshall & Bruce Co., Nashville, Tenn., a cor-
poration of Tennessee

Application May 15, 1931. Serial No. 537,560

6 Claims. (Cl. 101—77)

This invention relates to printing equipment and particularly improvements in rotary machines used for numbering sheets of paper stock such as blank book pages, receipt stubs, checks and record book pages, and the primary object of the invention is to provide such a machine which includes a plurality of rotatably mounted numbering-head wheels, each of which has a coacting impression roller and both of which are rotatably interconnected by trip and actuating apparatus designed to perform the function of maintaining the parts of the machine in continuous or intermittent operation so long as stock is being fed into the machine.

15 A yet further object of the invention is the provision of a numbering machine having a novel combination of parts which permits of great flexibility in the use of the machine and, by virtue of its construction, allows for greater capacity and virtually a positive operation which is carried on accurately and speedily without the use of complicated parts or expensive mechanisms.

20 A large number of minor objects will be included in the specification, referring to the accompanying drawings, wherein is illustrated a typical form of the invention now in successful use, and wherein:

Figure 1 is a top plan view of a rotary numbering machine embodying the invention.

Fig. 2 is a front elevation of the same taken from the feed-in end and having parts broken away for clearness.

Fig. 3 is a side elevation of one side of the machine.

Figs. 4, 5, and 6 are plan, side view and front view respectively of the novel inking mechanism built into the machine.

40 Figs. 7, 8 and 9 are enlarged detailed views of the detachable inking roller and its associated parts, all entirely removed from the assembled position.

Fig. 10 is an enlarged, fragmentary, plan view of two of the impression rollers and their related parts.

Fig. 11 is a fragmentary, vertical section through the machine along the side of one of the impression rollers and wheels.

50 Fig. 12 is a fragmentary, vertical section through a portion of the machine taken on line XII—XII of Fig. 11 with one-half of each roller and wheel left in elevation.

Figs. 13, 14 and 15 are, respectively, plan, front view, and side view of a typical numbering head

showing its attachment to one of the numbering-head wheels.

Fig. 16 is a perspective view of the especially formed rule made for use with the present numbering machine when setting the numbering heads.

Fig. 17 is a fragmentary, vertical section on line XVII—XVII of Fig. 2, illustrating the mechanism which allows wheels and rollers to come together to the printing position.

Fig. 18 is a fragmentary view of one set of bearings built into the machine for the two main shafts.

Fig. 19 is a fragmentary, plan view of a gripper and its associated mechanism.

Fig. 20 is a side elevation of the gripper and parts shown in Fig. 19, and,

Fig. 21 is a fragmentary showing of the gripper mechanism showing the same in the open position.

A machine of the character contemplated might include a large number of units, each of which may act upon the stock if desired, and at a predetermined time to properly position numbers at desired positions upon the stock as it passes through the device. In describing the machine it will be necessary to set down the specific structure of but one complete set of numbering parts. In the various views parts have not been duplicated where it was not necessary. For instance, any number of numbering heads might be used and any predetermined number of wheels and rollers might be incorporated, all in accordance with the size of the machine.

In constructing a numbering machine embodying this invention, the same should be supported by a frame 1, having a cross member 2 and a stay rod 3, all of which combine to make up a rigid foundation for the working parts of the mechanism. Frame 1 carries bearing hangers 166 at each side of the machine which support the rotatable lower shaft 9, and pillow blocks 177 carrying upper shaft 8. Shafts 8 and 9 are the main supporting shafts of the machine and carry the hereinafter mentioned wheels and rollers. Frame 1 also carries braces 5 which support an inclined feed table 6, from which paper stock is introduced into the machine. Arms 22 are also mounted upon frame 1 and carry a receiving table 23, pivotally secured, as shown in Fig. 3, to allow adjustment to any desired angle through the intermediacy of standard 24. Main frame 1 also carries cross rods 55 and 56, which are secured in place by suitable bolts and nuts in a well known manner. These rods 55 and 56 are util-

ized to support various elements of the machine as will hereinafter be set forth.

Upper shaft 8 and lower shaft 9 are both driven by a suitable source of power such as motor 15', 5 through a gear train which may consist of a pinion 13, large gear 12 and small pinion 11, driven by gear 12. Pinion 11 in turn drives two gears 10 of equal size, one of which is rigidly mounted upon shaft 8 while the other is likewise 10 carried by shaft 9. Motor 15' may be controlled through the intermediacy of an outlet box 107, conveniently positioned adjacent one corner of feed table 6. Electrical connection is made from motor 15' to outlet box 107 through flexible conduit 106, which may carry the necessary number of conducting wires. This outlet box 107 is constructed in a manner similar to those usually built into machinery of this character. As is known, continuous operation of the mechanism 15 might be affected when the operator depresses button 108. Stopping of motor 15' might be caused by depressing button 110, while button 109 is utilized for imparting intermittent or non-continuous movement to the machine.

25 This last mentioned and common expedient is oftentimes used for the convenience of the operator in moving the parts of the mechanism but a short distance so that adjustments may be made without trouble. Any number of numbering-head wheels may be included in this type of machine. In the instance shown, there are four in number, designated by numerals 14, 16, 18 and 20. These wheels are all mounted on shaft 8 for continuous rotation therewith, the preferable manner 30 of so mounting being through the use of a continuous key and key set. Coacting impression rollers 15, 17, 19 and 21 are mounted on shaft 9 for rotation therewith and in this instance individual keys are used to interlock shaft 9 and the 35 four impression rollers because of the presence of the support 4, positioned intermediate the ends of shaft 9. The reason for using keys and key ways is to permit of adjustment of the sets of wheels and rollers in a longitudinal direction along the 40 respective shaft 8 or 9. Each wheel 14, 16, 18 and 20, carries a cam 25 which actuates inking apparatus 115 forming a part of the machine and supported relatively stationary with respect to these 45 rotating wheels. Details of this inking apparatus 50 115 are hereinafter specifically set down.

As stock in the form of sheets of paper or similar matter enters the machine from table 6, the same passes between guides 7 which have been adjusted and secured in position by means of set 55 knobs 7'. The stock strikes trip lever 26 (shown clearly in Fig. 11), carried by rod 27, positioned in opposed relation to stop 28, supported by square rod 29. Rod 29 is oscillated by arm 30 and roller 30' which lies in the path of travel of cam 67 60 mounted on the side of one of the lower rollers carried by shaft 9.

In this instance roller 21 is illustrated. When roller 30' is riding over the face of cam 67, stop 28 is depressed below the edge of table 6 to allow the 65 stock to pass on between numbering-head wheels 14, 16, 18 and 20 and impression rollers 15, 17, 19 and 21, across guide 31 and thence between rollers 32 and 33. These rollers draw the stock along by virtue of the fact that roller 33 is positively 70 driven. Roller 32 is an idler, coacting with driven roller 33, receiving power from shaft 9 through pulley 34, belt 35 and pulley 36, mounted on the end of roller 33. From these rollers the stock is passed to receiving table 23 between 75 guides 37 and lined up against stop 38. Guides

37 and stop 38 are each adjustable to conform to the length and width of the stock to be received by suitable means 38', including the wing nuts, washers and bolts. After the passage of roller 30 over cam 67, the return of stop 28 to its original position, ready for another sheet of stock, is insured by spring 105, Fig. 10, mounted on the end of square rod 29 on which is carried stop 28.

80 Referring now to the apparatus insuring the operation of numbering-head wheels 14, 16, 18 and 20. Shaft 8, carrying these wheels has, at each end thereof, a cam 39, upon which is formed a depressed surface 39' (see Figs. 17 and 18). Cam 39 rotates with shaft 8 and as rotation takes place, shaft 8 is allowed to drop slightly because 85 roller 40, bearing upwardly against cam 39, enters depression 39'. When this relation is established, pressure against roller 40 is released, allowing arm 41 to loosen its grip on trigger 42 and, in case there has been placed a sheet of stock on table 6 90 against stop 28 and beneath lever 26, stop lever 43 will fall back from the position shown in Fig. 17 and away from engagement with trigger 42. Trigger 42 is now allowed to fall by the action of gravity and the weight of shaft 8 and parts supported thereby depresses roller 40, and arm 41 rises at the end opposite roller 40 to the limit imposed by the head of standard 44.

95 Thus the numbering-head wheels 14, 16, 18 and 20, and impression rollers 15, 17, 19 and 21 are 100 brought into contact or, in other words, to the printing position. In case there is no stock passing through the machine, counterweight 45, adjustable to any desired position along shaft 45', maintains stop lever 43, trigger 42 and arm 41 in 105 the position illustrated in Fig. 17. Vertical reciprocation on the part of shaft 8 is provided by using bearing blocks 48 floatingly mounted in pillow blocks 177. Their downward movement is limited against accidental falling by rod 46 and their upward movement is yieldably limited by spring 47.

110 It becomes desirable to keep a record of stock passing through the machine and to fulfill this 115 object of the invention, a counter 49' is provided and a lever arrangement, as shown in Fig. 17, incorporated so that when arm 41 is at the limit of its upward travel, arm 49 actuates the lever arm of counter 49' and a unit is registered.

At approximately the instant when depressed 120 surface 39' formed on cam 39 is resting on roller 40, grippers 50 are ready to grasp the edge of the 125 stock being introduced. Both the open and closed 130 positions of this gripper 50 is illustrated in Figs. 19, 20 and 21. In the more desirable form of the 135 invention, two grippers 50 are used, being mounted on adjacent faces or rollers 17 and 19. Figs. 19, 20 and 21 each show a part of roller 17. In the open position, Fig. 21, grippers 50 approach trip 140 51, idler 57 strikes trip 51 and as it is deflected downwardly, spring 58, in partial compression at all times, is still further compressed, until it is forced just past dead center in its travel and snaps over into the closed position shown in Figs. 19 and 20. Rod 58', attached with loose joint to 145 the back of gripper 50, passes through spring 58 to prevent same from getting out of line and, as gripper 50 changes from one position to another, rod 58 reciprocates through a hole in holder 59.

150 When gripper 50 has caught the sheet of stock and pulled it inwardly a sufficient distance to allow rollers and wheels to continue the drawing force, idler 57 strikes member 52 to snap gripper 50 back into the open position. This action is exactly the reverse of the closing opera-

tion. Member 52 is mounted on bar 54, suspended between cross rods 55 and 56, and is adjustable to any required position. Each one of the impression rollers forming a part of the machine has cut out of the web 60 thereof, a segment 60', similar to that shown in Fig. 11, and has an opening 61 formed through the roller flange the full width of the shallow annular groove 62 formed in the face of the flange (see Fig. 12). Groove 62 of each roller has a pad 62' therein made up of some suitable firm, soft, material, covered by a strip of smooth sheet material 64, such as paper, canvas or the like. The ends of this material 64 are brought through opening 61 and over curved pieces of metal 63. The ends of this material are left loose, as shown at 64 in Fig. 11. Thus material 64 is held in a stretched condition around the rollers by the wedge-shaped piece 65, held in place by spring 66. Spring 66 may be held in line by a lug on the back of wedge 65.

The purpose of pad 62' and material 64 is to provide a surface upon which numbering heads 144 may strike when an impression is made, without damaging the type faces and the arrangement shown provides an easy, rapid way of removing the padding when same becomes packed or worn, or of providing a clean, smooth covering material 64 when the one in use becomes worn or stained from use. These novel features insure high quality work and prevent "offsetting" from a dirty printing surface. Numbering-head wheels 14, 16, 18 and 20, carried on shaft 8, may each support a numbering head 144, a typical showing being in Figs. 1 and 2. Numbering head 144, as well as inking apparatus 115 has not been shown in connection with all of the wheels, it being sufficient to disclose the invention by an illustration of but one complete unit.

Details of numbering head 144 are shown in Figs. 13, 14 and 15. The numbering head 144 itself is a stock product and may be of any suitable type well known to the trade. Its combination and location, as well as parts for supporting the same in operative relation, are new. Holder 68 is designed to fit between the flanges of wheel 20, and the base of the holder is made to fit the annular surface thereof. Holder 68, supporting numbering head 144, is held in rigid position on the roller by set screws 70, screwed into lug pieces 69. These lug pieces 69 have beveled edges and are designed to slip to annular grooves 72 through opening 71, both formed in the annular face of each roller 14, 16, 18 and 20. Groove 72 is undercut to prevent lug 69 from falling out. But one opening 71 is provided in each wheel and all entries for any number of heads 144 used on that particular roller might be made through this single opening 71. The position of opening 71 should be opposite depressed surface 39' on cam 39 and also in proper relation with opening 61 in roller 21. Since no printing takes place at this point on roller 21, no numbering head 144 should appear between the rollers at that point. In practice, this point is deemed the beginning of the printing travel. Set screw 73 in holder 68 might be utilized to secure numbering head 144 in place. Cam 67 on roller 21 is positioned as shown in Fig. 11 with reference to opening 61, so that as the end of the same is engaged by roller 30' which actuates paper stop 28, opening 61 will be just ahead of the top of the sheet of stock to be numbered, and will be cleared when stop 28 has been

depressed and the sheet begins to pass beneath the upper numbering-head wheels.

To provide means for automatically disposing a freshly inked roller for each revolution of the number head 144, a stationary inking apparatus 115 is mounted on rod 74 adjacent each wheel 14, 16, 18 and 20. This apparatus 115 is designed as shown in Figs. 4, 5 and 6.

To actuate this apparatus each wheel is provided with a cam 25, disposed to strike idler roller 75 of apparatus 115 to depress the same in the direction of the arrow shown in Fig. 5, as roller 75 passes over cam 25. This action moves lever 76 to pull down on connecting rod 77, which moves spindle 78, causing grooved roller 79 to move over and come in contact with inking roller 80. This roller may be made of rubber, fiber, or similar material and runs in contact with ink drum 81, which receives a coating of ink from a supply kept on plate 82. Ink intermittently taken up by roller 79 is transferred to roller 83 which comes in contact with type faces of numbering head 144. Proper pressure of roller 83 against the type faces is gauged and definitely fixed by tracking rollers 84 moving on flanges of the numbering-head wheel. In order that a supply of ink might be fed constantly and not too rapidly to ink drum 81, a ratchet arrangement is utilized, actuated by connecting rod 77. Each time cam 25 strikes roller 75 and passes therebeyond, an up and down motion of connecting rod 77 takes place. Ratchet 85 advances one tooth and with it drum 81. Pressure of plate 82 against drum 81 is regulated by a thumb set screw mounted on a spindle 86. Arm 87 is not connected to ratchet 85, but carries a pawl and coil spring 88 and is pivoted to the end of connecting rod 77 to serve the purpose of conveying the tension of spring 88 so that the lever 76 and roller 79 will be maintained in a forward position ready to ride along cam 25. Roller 79 has considerable lateral play in its spindle, which is provided for a purpose. When roller 83 is engaging the type face and is in contact with roller 79, the grooved face of roller 79 tends to cause the same to move across the face of roller 83 to procure an even distribution of ink.

In order to make this action effective, it must be repeated each time and hence as roller 79 is brought back into contact with roller 80, the end of the spindle of roller 79 projects beyond the bearing and strikes spring 89 which flips the spindle and roller 79 back to the opposite side ready for the next inking operation.

Roller 80 is removable for purposes of cleaning and replacing. A detail of the same is shown in Figs. 7, 8 and 9. Fig. 7 is a perspective view of spindle 101 of roller 80, the chief feature of which is flange 101' forming a stop for the roller proper. Lug 102 engages notch 103 in bushing 104 of roller 80 and when assembled, spindle and roller form a rigid unit. Between the sides of inking mechanism 115 is inserted split collar 90 (see Figs. 5 and 6). Heavy spring 92, inserted into collar 90, exerts tension against spacer 93. When the desired thrust of inking apparatus 115 is reached split collar 90 is fastened rigidly in place by set screw 91.

A special gauge for use with this machine is shown in Fig. 16. This gauge consists of a curved bar 95, on which is carried movable stops 96 and 97, each having a set screw 100 for fixing the same at proper points. On the side of bar 95 is etched or otherwise marked, a scale having divisions 105 145 150

which are radial projections of circumferential inches (in sixteenths), figured on an arc of a circle through points 98 and 99 of the two stops 96 and 97. The radius of the circle passing through these two points 98 and 99 will be the same as the radius of the circle passing through the points to be considered when setting numbering heads 144, shown in Figs. 13, 14 and 15, which would be the bottom of the row of numerals or type faces 1, 10 2, 3, 4, 5, 6, (Fig. 13).

In using the device when stock with multiple blanks are to be numbered, a measurement on a plane surface is taken between the two or more blanks in regular inches and sixteenths; the stop 15 96 of bar 95 is set at zero on the scale and stop 97 adjusted to read a similar number of inches and sixteenths on the curved bar 95. Automatically, points 98 and 99 will be set so that in spacing the numbering heads 144 the application of points 98 20 and 99 will accurately and quickly space said heads so that when printing begins the numbers will be inserted exactly in the proper blank spaces on the stock.

It is understood that many modifications might 25 be made when constructing a machine in accordance with this invention.

Having thus described the invention, what is claimed as new and desired to be secured by Letters Patent is:

- 30 1. A rotary numbering machine comprising a numbering-head wheel; an impression roller associated for synchronous movement therewith; and apparatus operable upon admitting stock to the machine, for permitting the wheel to move to the stock numbering position, said apparatus being actuated by an arm disposed in the path of travel of the stock.
- 35 2. A numbering machine comprising a rotatable wheel and coacting impression roller; apparatus 40 to cause relative movement of said wheel and roller toward and from each other; at predetermined times; a numbering head carried by said wheel at the annular periphery thereof; a relatively stationary inking apparatus for the numbering head; and means connecting said numbering head and wheel whereby adjustment to the desired position on the periphery of said wheel may be affected, said means including an annular un-

50

55

60

65

70

75

dercut slot, a lug-piece slidably mounted within said slot, and members interconnecting the lug piece and numbering head, said slot having outwardly converging sides and an entrance opening to permit the introduction of said lug-piece into the said slot.

3. In a rotary numbering machine, a rotatable wheel; a numbering head adjustably mounted thereon; an impression roller; and apparatus, operable as said wheel is rotated, for admitting stock to the machine and disposing said wheel and roller in the printing position including a cam mounted on the impression roller, a roller disposed in the path of travel of said cam, and a stop movable to permit entrance of stock into the machine when the cam is in engagement with said roller.

4. In a rotary numbering machine, a rotatable wheel; a numbering head adjustably mounted thereon; an impression roller; and apparatus, operable as said wheel is rotated, for admitting stock to the machine and disposing said wheel and roller in the printing position including a cam mounted for rotation with said wheel, an arm and roller limiting the movement of said cam and wheel, and a trigger, operable to the released position by stock as it is being fed into the machine, whereby the wheel is permitted to drop into engagement with said impression roller.

5. In a numbering machine, having inking apparatus a plurality of numbering head wheels; a plurality of impression rollers; means for moving said wheels toward and from the rollers including a cam carried by each of said rollers respectively; a numbering head adjustably affixed to the annular periphery of each wheel respectively; and a cam mounted on each wheel to engage and operate the said inking apparatus.

6. In a numbering machine, a numbering head wheel; flanges projecting radially at the annular edge of said wheel; a numbering head; a groove formed in the annular face of said wheel and a lug slidably mounted in said groove to receive and support said numbering head at any predetermined point around said wheel, said numbering head resting between said flanges.
